US00D874685S

(12) **United States Design Patent** (10) **Patent No.:** **US D874,685 S**
(45) **Date of Patent:** **** Feb. 4, 2020**

(54) **PANEL**

(71) Applicant: **Dolby Laboratories Licensing Corporation**, San Francisco, CA (US)

(72) Inventor: **Paul Frick**, San Francisco, CA (US)

(73) Assignee: **Dolby Laboratories Licensing Corporation**, San Francisco, CA (US)

(**) Term: **15 Years**

(21) Appl. No.: **29/672,813**

(22) Filed: **Dec. 10, 2018**

Related U.S. Application Data

(63) Continuation of application No. 29/568,630, filed on Jun. 20, 2016, now Pat. No. Des. 839,452.

(51) **LOC (12) Cl.** **25-01**

(52) **U.S. Cl.**

USPC **D25/138**

(58) **Field of Classification Search**

(57) **CLAIM**

The ornamental design for a panel, as shown and described.

DESCRIPTION

FIG. 1 is a front view of a panel showing my new design in an environment of use;

FIG. 2 is a front view thereof;

FIG. 3 is a rear view thereof;

FIG. 4 is a top view thereof;

FIG. 5 is a bottom view thereof;

FIG. 6 is a front, right perspective view thereof; and,

FIG. 7 is another perspective view thereof.

The broken lines in FIG. 1 illustrate environmental subject matter which forms no part of the claimed design. The broken lines in FIGS. 3, 5, and 7 illustrate portions of the panel which form no part of the claimed design.

1 Claim, 5 Drawing Sheets
